ROBERT A. GALLY, OF CINCINNATI, OHIO, ASSIGNOR TO THE BALDWIN COMPANY, OF CINCINNATI, OHIO.

MUSICAL-INSTRUMENT RESERVOIR-CHECK.

1,265,190.

Specification of Letters Patent.

Patented May 7, 1918.

Application filed August 2, 1917. Serial No. 184,141.

To all whom it may concern:

Be it known that I, ROBERT A. GALLY, a citizen of the United States, and residing at Cincinnati, county of Hamilton, and State 5 of Ohio, have invented certain new and useful Improvements in Musical-Instrument Reservoir-Checks, of which the following is a specification.

Player pianos having a pneumatic action, 10 with the air service for such an action supplied by both a power drive and a foot drive to the bellows or other wind inducing apparatus, have formerly been provided with check valves to hold out of air connection whichever one of said air inducing 15 means was not utilized at that time of operation, while in the present invention the main air chest and the air tension reservoir are always in air connection with the player 20 action whenever that action is being operated, a mechanical locking means or check being provided which prevents the motion of the said reservoir when the power pumping means is operated, but allows the motion 25 of the said reservoir when the foot pumping means is operated, a convenient additional feature being the connection of the said check to the handle for opening and closing the door of the opening to the 30 foot of the foot pumping devices, or may be connected to any shiftable element or such other parts which by their shifting correspond to the proper conditions for foot or power operation or any other dual condition 35 or purpose.

In the drawings Figure 1, is a front view of the lower part of a player piano with its slide door open, the foot pumping pedals swung out for operation, and the check released from the air tension reservoir to allow 40 the suction of that reservoir; and Fig. 2, is the same view with the foot pedals thrown in, the slide door closed, and the check locked against the motion of the reservoir; 45 and Fig. 3, is a larger scale view of the details of the check: In both Figs. 1 and 2, the lower frame or panel board of the piano has been removed to exhibit the parts important to this application; but it is to be 50 understood that such a lower frame is usually in place in front of all this lower part of the piano, an opening being provided in said frame for the throwing in and out of the foot pedals, such opening being closed

by the slide door whenever said door is 55 thrown to its closed position as in Fig. 2.

A general wind chest 1 has two pumpers 2, and 3, connected to the chest 1 by the usual valved ports, each said pumper having any suitable mechanical connections as 60 to their corresponding foot pedals 5, 6. A power driven pumper as 7 is connected by suitable means as a belt 8 to an electric motor 9 or other power means. An air pipe 10 or other service connection leads from 65 the power pumper 7 to the wind chest 1 and a check valve as 11 may be provided to prevent back suction of air from the power pumper 10 when the foot pumpers 2, 3 are 70 operated.

A check valve 12 of a bail form is hung by its upper ends 13 from the key bed 14 or other solid part of the apparatus adjacent the moving board 15 of the reservoir 16, fixed 75 bearings as 17 being provided in which said 13 ends are revolubly mounted. This enables the check 12 to be swung to a position free of the said reservoir board 15 as in Fig. 1, then allowing a full expansion 80 and motion of the said reservoir board 15 for steadyng the air during the alternate action of the pumpers 2, 3 during foot pumping, or that the said check can be swung to a position checking the said reservoir board 15 to a position partly or wholly 85 restricting the motion of the said board 15 during the air service by the power driven pumper 7 as shown in Fig. 2, which is usually desirable during such power pumping, 90 as very quick charges of air tension are then desired for automatic accent of the music, and any motion of a reservoir would cause that much loss of time in raising the tension, as such reservoirs suitable for foot pumping uses are usually of low tension 95 rating, high tensions being secured by the foot operation by a carefully prepared building up of the tension, or a very sudden action by the foot pumpers, such quick action being much faster than is desirable for a 100 power pumper, especially if such power pumper is of constant speed, as is usual.

The check 12 is swung to and from its position of limiting the motion of the reservoir board 15, by means of a link 18 connected to the slide door lever 19, which lever 19 has a handle 20 at its upper part, and at its lower part is a link 21 connecting

said lever 19 to the slide door 22. The link 18 has a slot 23 or other equivalent lost motion device at the engagement of said lever 18 to the check 12, which engagement is made on a pin 24 on a bracket 25 attached to the front arm 26 of the check 12, the pin 24 being at such a position relative to the revoluble ends 13 as will enable the easy swing of the check 12 10 on its revoluble ends 13 by the substantially straight line motion of the link 18. The upper end of the lever is shown as bent forward in a horizontal shaft held in suitable bearings 20^a on the keybed 14 or other 15 part of the case, so that the lever 19 may be swung by the handle 20 which depends from the forward end of the said shaft part.

When the instrument is idle and it is desired to start the power pumping, attention 20 is given that the handle 20 and lever 19 are at their rightward position as in Fig. 2, the door 22 being closed as is desirable to exclude any operating sounds of the motor and power pumper. Before the power pumping 25 is started the reservoir 16 is in expanded condition, its moving board 15 being at its upper position, but the handle 20, lever 19 and link 18 being at their rightward position, as the latter parts are shown in Fig. 3, 30 the check 12 then resting on the upper board 15. As the operation of the power pumper 7 is started the suction therefrom through pipe 10 and chest 1 serves to collapse the reservoir 16 against its expansion spring 27, and as the said board reaches the 35 desired position for partially or wholly limiting any later motion of said board 15, the check 12 swings down into the position shown in Fig. 2, thereby limiting the motion 40 of said board 15 until it is desired to use the foot pumbers, when a leftward movement of the handle 20, lever 19 and link 18, will pull the check 12 to the left and swing it upward to the position shown in Fig. 1, 45 the reservoir board 15 then being free to move and allow the storage and the steady- 50 ing of the air action by the reservoir 16. The slot 23 in link 18 is provided so that when the handle 20, lever 19 and link 18 are 55 thrown to the right when no pumping is being done and the reservoir board 15 is then in its expanded position as in Fig. 3, the link 18 is allowed to reach its extreme rightward position, its slot 23 then extending to 60 the right of the pin 24 so that when the board 15 is drawn away from said chest 12, the said check can swing down and to the right to a locked position against the board 15. Any spring means can be added to the 65 check 12 to assist its swinging to the locked position at the right.

A reservoir as 16 having an interrupting block as 28 to cause a slanted position toward the swinging motion of the check 12 65 aids the easy operation of said check 12,

although a constantly parallel action board, or a slanted or end hinged reservoir may be employed, as such items and others are mere mechanical details, unessential to the broader merits of the present invention; although 70 the use of the present reservoir check 12 in combination with a reservoir moving board as 15 resting at two distant points 28, 29 when restricted by the check 12, secures a desirable yielding action of the board on 75 very high tension of air, increasing the effect of such high tension of air on the music playing parts. The interrupting block reservoir herein shown is similar to the applicant's prior Patent #1,034,098, and the slide 80 door operating device is similar to that shown in this applicant's prior Patent #1,103,193.

What I claim as my invention:—

1. A collapsible and expandable air reservoir having a moving board and a check mounted to be moved into and away from a position to interrupt all motion of the said board at one certain position of the said board; a shiftable element independent of the said moving board; and a shifting element connected to the said shiftable element and to a movable part of the said check. 85

2. A collapsible and expandable air reservoir having a moving board and a check swingably mounted to be moved into and away from a position opposed to the expansion motion of said moving board; a shiftable element independent of the said moving board; and a shifting element connected 95 to the said shiftable element and to a movable part of the said check. 100

3. A collapsible and expandable air reservoir having a moving board and a check swingably mounted to be moved into and 105 away from a position to interrupt all motion of the said board at one certain position of the said board; a shiftable element independent of the said moving board; and a shifting element connected to the said shiftable element and to a moving part of the said check. 110

4. A collapsible and expandable air reservoir having a moving board and a check mounted to be moved into and away from 115 a position to restrict the motion of the said moving board, a shiftable element independent of said moving board; and a shifting means connected to the said shiftable element and to a moving part of the said 120 check.

5. A collapsible and expandable air reservoir having a moving board and a check mounted to be moved into and away from a position to restrict the motion of the said 125 moving board; a movable door, and a shifting means connected to the said movable door and to the said check.

6. A collapsible and expandable air reservoir having a moving board; air pumper 130

means and foot pedals for their operation; air pumper means and power means for their operation; and movable check mounted to be moved to and away from a position to restrict the operation of the said moving board during the operation of the said power pumping means.

7. A collapsible and expandible air reservoir having a moving board; foot operable air pumper means and power operable air pumper means; and a movable check mounted to be moved into and away from a position to restrict the operation of the said moving board during the operation of the said power pumping means.

8. A collapsible and expandible reservoir having a moving board, and a check mounted to be moved into and away from a position opposed to the expanding motion of

the said board; and controlling means connected to the said check and having a lost motion element intermediate the said controlling means and the said check.

9. A collapsible and expandible reservoir having a moving board, and a check mounted to be moved into and away from a position opposed to the expanding motion of the said board; and controlling means connected to the said check and having a lost motion element intermediate the said controlling means and the said check; and an additional and shiftable element independent of the said moving board and connected to and shiftable by the said controlling means.
